UNITED STATES PATENT OFFICE.

BARRY MACNUTT, OF SOUTH BETHLEHEM, PENNSYLVANIA.

CARBURETER FOR INTERNAL-COMBUSTION ENGINES.

1,097,554.

Specification of Letters Patent. Patented May 19, 1914.

Application filed January 3, 1911. Serial No. 600,481.

To all whom it may concern:

Be it known that I, BARRY MACNUTT, a citizen of the United States, residing at South Bethlehem, in the county of Lehigh and State of Pennsylvania, have invented 5 certain new and useful Improvements in Carbureters for Internal-Combustion Engines; and I do hereby declare the following to be a full, clear, and exact description of the invention, such as will enable others skilled in the art to which it appertains to make and use the same.

My invention relates to carbureters for internal combustion engines.

15 This carbureter is designed to use the lower grades of fuel, such as petroleum and crude oil.

20 My aim is to effect the vaporization of the fuel in an improved and more efficient manner whereby the capacity of the carbureter is greatly increased and a superior quality of vapor is produced.

25 The invention consists generically of a series of electrically heated grids arranged transversely in the carbureter between the fuel inlet and vapor outlet.

30 The invention also consists in the features or construction and combinations of parts hereinafter described, illustrated in the accompanying drawing and specified in the claims.

35 In the accompanying drawing: Figure 1 is a central vertical sectional view of a carbureter constructed in accordance with my invention. Fig. 2 is a horizontal section taken on the line $x-x$ of Fig. 1, and Fig. 3 is a similar section taken on the line $y-y$.

40 Referring more particularly to the drawing, 1 designates the casing having the air intake pipe 2 and the pipe 3, leading from the casing, entering near the bottom thereof. The fuel supply pipe 4 enters the top of the casing and delivers into a chamber 5 formed between the top of the casing and 45 a horizontal partition 6. Said partition is provided with openings or nozzles 7 distributed over its entire surface whereby the fuel is delivered in the form of a shower into the main portion of the casing.

50 Intermediate of the partition 6 and the plane of the pipes 2 and 3, there are arranged in the casing a plurality of horizontal grids 8, preferably spaced equi-distant apart. Each grid consists of a ring 9 55 of insulating material and a flat coil of wire extending across said ring, the bends

of the coil being seated in said ring. Said ring conforms to the interior of the casing and is secured in position in any suitable manner, such as by the screws 10. The cross pieces of each grid, namely, the parallel portions of its wire coil extend transversely to those of the adjacent grid or grids.

50 The several grids may be connected in series, parallel, or in any other manner. I have shown them connected in series. The terminals of said grids are connected to a suitable electric generator. While I have shown only three grids, it will be understood that a greater or less number of them may be employed to suit conditions.

55 In operation, the shower of fuel from the nozzles in the partition 6 comes in contact with the several grids, in order, percolating through first one and then another until, 70 when it passes through the last and lowest grid, it has become completely vaporized and is in condition to form the proper admixture with the air for delivery to the cylinder of the engine.

60 Changes may be made in the details of construction of the devices herein shown and described without departing from the spirit or sacrificing the advantages of my invention. I, therefore, reserve the right to make 75 such alterations and adaptations as may fairly fall within the scope of my invention. For instance, the grids may be formed in numerous other ways and of other materials than a continuous coiled wire.

80 I claim:

1. A carbureter, of the character described, having a liquid fuel-supply port, an air intake port, and a vapor outlet port, an electric conductor in the form of a grid arranged transversely of the carbureter between said fuel-supply and vapor outlet ports, and an electric generator connected to said conductor for heating the grid, said air intake port being arranged on the same side of the grid as the vapor discharge port whereby the liquid fuel is obliged to pass through said grid before it is mixed with the air and passes out of the carbureter.

95 2. A carbureter, of the character described, comprising a casing having a liquid fuel-supply port, an air intake and a vapor outlet port, a grid extending entirely across the casing between the fuel-supply and vapor outlet ports, said grid comprising a frame of insulating material, suitably secured to the inner surface of the casing, and

- a bent electric conductor extending across said frame with its bends embedded therein, and an electric generator connected to said conductor for the purpose specified.
- 5 3. A carbureter, of the character described, comprising a casing having a liquid fuel-supply port, an air intake and a vapor outlet port, a grid extending entirely across the casing between the fuel-supply and 10 vapor outlet ports, said grid being detachable bodily from the casing and comprising

a frame of insulating material, and a bent electric conductor extending across said frame with its bends embedded therein, and an electric generator connected to said conductor for the purpose specified. 15

In testimony whereof, I affix my signature, in presence of two witnesses.

BARRY MacNUTT.
